(57) **CLAIM**

The ornamental design for a wooden fence, as shown and described.

DESCRIPTION

FIG. 1 is a top, front, right side perspective view of a wooden fence showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof, and,

FIG. 8 is a bottom plan view thereof.

The dash-dot-dash broken lines define the boundary of an enlarged view and form no part of the claimed design.

1 Claim, 8 Drawing Sheets
